TUYÈRE BLOCK

Herbert E. Preston, Philadelphia, Pa., assignor to
American Engineering Company, Philadelphia,
Pa., a corporation of Pennsylvania

Application June 21, 1928. Serial No. 287,277

4 Claims. (Cl. 110—44)

My invention relates to tuyères, and it has for one object the provision of a tuyère that is particularly applicable to stokers of the inclined underfeed type.

Considerable difficulty and much inconvenience has been occasioned in the use of highly preheated air with certain types of tuyères wherein the outlets of the air passages are directly in the beveled side walls of the forward exposed or nose portions of the individual blocks since the molten slag flows through the fuel bed onto the tuyères and covers the air openings, effectually blocking the passage of air therefrom. The clogging of the air openings results in the rapid heating of the adjacent metal portions of the tuyère and subsequently the destruction of the noses of the tuyère blocks. Another object of my invention, therefore, is to provide a stoker tuyère block so constructed as to overcome these undesirable results.

Other objects and applications of my invention, as well as details of construction and operation thereof, whereby the same may be practiced, will be apparent more fully hereinafter, when taken in connection with the accompanying drawing, wherein

Figs. 1 and 2 are top plan and side elevational views, respectively, of a stoker tuyère block embodying my invention;

Fig. 3 is an end elevational view looking from the rear end of the block; and

Figs. 4 and 5 are longitudinal sectional views, taken on the lines 4—4 and 5—5, respectively, of Fig. 1, Fig. 4 illustrating by means of broken lines the interrelation of the tuyère blocks in the tuyère assembly.

Referring to the drawing, the stoker tuyère block therein shown, which is one of a series constituting the tuyère, comprises a main body portion 1 in the form of a flat, thin plate having a rear portion 2 and a forward portion 3, the said forward portion constituting in the assembled tuyère the exposed or fuel-supporting section of the block. The portion 2 is provided with parallel, longitudinally-extending side edges 4 and 5, while the portion 3 is provided with curved side edges 6 and 7 which terminate in a rounded, end edge portion 8. An aperture 9 is formed in the rear plate portion 2 for the reception of a similarly formed projection 11 which depends from a tuyère disposed immediately above the same. The projection 11 extends from an underside 12 at a point approximately midway between the side edges 4 and 5 and forwardly of, but in longitudinal alignment with, the opening 9.

The tuyère block is supported in position on the next adjacent block of the series by means of a pair of side projections 13 and 14 and an end projection 15. The undersides 16 of the projections or lugs 13 and 14, and the underside 17 of the end projection or lug 15 are positioned in a common plane and constitute the main block-supporting surface. The lug 15, which is positioned in longitudinal alignment with the lug or projection 11, comprises a depending portion 18 of L-shape. An aperture 19 is formed in the forward or nose portion 3 of the tuyère block in longitudinal alignment with the lugs 11 and 18, and it is adapted to receive the lug 18 of the next higher block. The lug 18 of the block shown in Fig. 2 is adapted to enter the opening 19 of the next lower tuyère block. The lugs 11 and 18 thus assure the locking of each block in position.

Since the underside 12 of the block is spaced from the next lower block by means of the lugs 13, 14 and 15, an air chamber is formed which may be connected in the usual manner with the air box of a stoker (not shown). Inasmuch as it is desirable to cause the air to discharge from the nose 3 in a predetermined manner, a group 20 of fins or ribs 21 are positioned on the underside of the block between the end supporting lug 15 and the side lug 13, while a second group 22 of ribs or fins are positioned between the supporting lug 15 and the side lug 14, as shown in Fig. 1. The fins 21 in the group 20 are formed with a progressively increasing length and decreasing pitch from the side lug 13 to the end lug 15. The fins 21 in the group 22 are similarly varied in length and pitch between the side lug 14 and the centrally positioned end lug 15. Thus, a plurality of channels 23 are formed which progressively increase in length between the side and end ribs in each group, and which in the tuyère assembly constitute the air passages.

One of the features of my invention is the provision of a tuyère, wherein the forward or outlet openings 25 of the air passages 23 are prevented from being blocked by the molten slag passing down through the fuel bed of a furnace. To this end, I provide in each tuyère block a marginal recess 26 which comprises side portions 27 and 28 and an intermediate portion 29. The side portions 27 and 28 are coextensive with the inclined edges 6 and 7 of the nose and are positioned just inwardly of the same, while the portion 29 is positioned inwardly of the forward edge portion 8. An outer part of the marginal recess 26 is formed by terminating the fins 21 and 22 inwardly of the edges 6 and 7, as shown

in Fig. 1. A curved overhanging portion 30 is thus formed which in the tuyère assembly is in spaced relation to the upper side of the next lower tuyère, so that a cross channel is provided inwardly of the edges 6, 7 and 8 which embraces the entire forward edge of the block and connects the forward or discharge ends of the air passages 23.

My invention embodies the still further feature of beveling or inclining the forward ends 31 of each of the fins 21, as shown in Fig. 1, to provide an open space between each of the edge portions 31 and the upper side of the next lower tuyère. These open spaces form in the assembly a marginal or cross air-passage constituting an inner part of the passage 27, and further assure the interconnection of the outlet openings 25 of the air passages 23 in the event that the outer marginal part of the air passage, which is between the ends of the fins 21 and the edge 6 of the tuyère block, should become obstructed. The length or angle of the beveled portion 31 at the forward end of each fin is progressively decreased in length from the side lug 13 to the end lug 15, thereby providing air outlet openings for the passages 23 which also progressively decrease in length. The rear ends of the fins 21 are also provided with beveled portions 32 which are opposite to the beveled portions 31 at the forward ends thereof. The fins 21 in the group 22 are similarly provided with rear beveled portions 33 and forward beveled portions 34, the latter in the assembly forming a cross passage constituting an inner part 35 of the marginal air passage 28. The fins 21 of this group also terminate just inwardly of the side edge 7 to form an outer part 36 of the marginal air passage 28.

An outer part of the intermediate marginal passage 29 is formed by spacing the forward side 37 of the supporting lug 15 from the edge portion 8 to form an overhanging shoulder portion 38. An inner part of the end passage 29 is formed by providing the side 37 with a curved portion 39, as shown in Fig. 2. The inner part further decreases the danger of the marginal cross passage 29 being closed by molten slag. Sides 40 and 41 of the lug 15 may also be beveled to assure a desired air distribution.

In operation, should molten slag flow over one or more portions of the forward tuyère edges 6, 7 and 8, the air passages adjacent to the covered edge portions are not blocked, since the air passes through the outlet openings 25 of these air passages into the marginal recess 26 and from there into the furnace through the edge portions which have not been covered. Should the slag extend inwardly so as to cover the outer marginal part of the recess 26, there would still remain the inner part which extends

around the entire forward edge portion of the tuyère nose 3. Should a condition develop wherein the slag completely prevents the passage of air outwardly through the side edge 7, the edge 8 and all but a portion 46 of the side edge 6 of any of the blocks, the tuyère would still not be damaged, inasmuch as the air passing into the passages 23 of the group 22 circulates through the marginal recess portions 27, 28 and 26, finally leaving the tuyère through the unobstructed part 46.

While I have shown only one form of embodiment of my invention, for the purpose of describing the same and illustrating its principles of construction and operation, it is apparent that various changes and modifications may be made therein, without departing from the spirit of my invention. I desire, therefore, that only such limitations shall be imposed thereon, as are indicated in the appended claims or as are demanded by the prior art.

I claim:

1. A tuyère block adapted for arrangement in a stepped series with similar blocks to form tuyères, said block comprising a plate having a plurality of channel-forming ribs terminating inwardly of the forward edge of the plate and having their forward edges beveled.

2. A tuyère block adapted for arrangement in a stepped series with similar blocks to form tuyères, said block comprising a plate having a plurality of channel-forming ribs, said ribs having their forward end edges beveled and terminating inwardly of the forward edge of the plate, and said beveled end edges forming acute angles with the plane of the face of said plate from which the ribs project.

3. A tuyère block adapted for arrangement in a stepped series with similar blocks to form tuyères, said block comprising a plate having parallel straight edge portions, and a curved edge portion connecting said parallel edge portions, a supporting lug on the medial line of the plate, a series of diverging ribs on each side of the medial line, the outer ends of said lug and ribs being spaced inwardly from the curved edge of the plate and inclined, said ribs being spaced one from another, and the lug being spaced from the adjacent ribs to form air channels communicating with the space at the outer ends thereof.

4. A tuyère block having a forward substantially horizontal fuel-supporting portion and a plurality of ribs depending from the underside and forming air channels extending toward the forward edge of said fuel-supporting portion, the forward ends of said ribs being beveled downwardly and rearwardly.
